(57) **CLAIM**

The ornamental design for an animal grooming comb, as shown and described.

DESCRIPTION

FIG. 1 is a perspective view of an animal grooming comb embodying our new design;

FIG. 2 is a bottom plan view thereof;

FIG. 3 is a front elevation view thereof with the handle shown in full lines centered on the tines and shown in broken lines in extreme positions on the tines;

FIGS. 4 & 5 are right and left end views, respectively, thereof;

FIG. 6 is a top plan view thereof; and,

FIG. 7 is a rear elevation view thereof.
